UNITED STATES PATENT OFFICE

ALBERT F. HARTMAN, OF SAGINAW, MICHIGAN

DESIGN FOR A SIGNALING DEVICE

Application filed October 4, 1929. Serial No. 32,951. Term of patent 14 years.

To all whom it may concern:

Be it known that I, ALBERT F. HARTMAN, a citizen of the United States, residing at Saginaw, in the county of Saginaw and State of Michigan, have invented a new, original, and ornamental Design for a Signaling Device, of which the following is a specification, reference being had to the accompanying drawing, forming a part thereof.

The figure is a perspective view of a signaling device, showing my new design.

I claim:—

The ornamental design for a signaling device as shown.

ALBERT F. HARTMAN.
